UNITED STATES PATENT OFFICE.

EUGENE E. KEHNERT, OF LORAIN, OHIO, ASSIGNOR TO WILLIAM E. KAY, OF LORAIN, OHIO.

WATER-HEATER.

No. 863,402.

Specification of Letters Patent.

Patented Aug. 13, 1907.

Application filed May 18, 1906. Serial No. 317,487.

To all whom it may concern:

Be it known that I, EUGENE E. KEHNERT, a citizen of the United States, and a resident of Lorain, in the county of Lorain and State of Ohio, have invented 5 a new and Improved Water-Heater, of which the following is a specification.

My invention is an improvement in that class of water heaters adapted for domestic and shop use, in which the water is heated by gas, and the volume of 10 the latter admitted to the burner is automatically regulated by the quantity of hot water drawn off. I dispense with springs, stuffing-boxes, and some of the other usual adjuncts of heaters of this class, and I arrange the gas and water controlling valves, and means 15 for operatively connecting them, in one and the same casing or inclosure, whereby I attain a maximum simplicity, durability, and efficiency in operation.

The details of construction, arrangement, and operation of parts are as hereinafter described, reference 20 being had to the accompanying drawings, in which

Figure 1 is in part a side view and in part a vertical section of my improved water heater and its attachments. Fig. 2 is a horizontal section on the line 2—2 of Fig. 1. Fig. 3 is a side view; and Fig. 4, a plan 25 view of the burner proper forming one of the heater attachments. Fig. 5 is a central vertical section of the gas and water controller. Fig. 6 is a vertical section on the line 6—6 of Fig. 5. Fig. 7 is a cross-section on the line 7—7 of Fig. 5. Fig. 8 is a section on the line 8—8 of Fig. 5. Fig. 9 is a perspective view 30 of the lever connecting the gas and water valves. Fig. 10 is a perspective view of the tapered bearing for the aforesaid lever.

In Figs. 1 and 2, A indicates the casing, or shell, of 35 the water heater, B, a water coil arranged therein, C, a burner located below the coil, and D, the casing inclosing the gas and water valves, the same being connected with the coil B and burner C, as will be presently described.

40 The coil and burner are supported from the top of the casing A by a rod 1, and a drip pan E is applied below the burner and the two secured together and to the pendent bar 1 by means of a long screw-bolt 2. The said pan E serves to receive water of condensation. 45 It is provided with a central boss 3 which abuts and closes the lower open end of the hollow cylinder 4 constituting the central portion, or body, of the burner—see Figs. 1 and 2. From said cylinder 4 diverges a series of bars 5 at an angle of about 45°, their outer 50 upper ends being connected by a ring 6 that extends downward a short distance on the same inclination as the bars. Upwardly inclined gas passages 7 are formed in the cylinder or body 4 between the several bars 5. It will be seen that the gas admitted to the cylinder 4 discharges upward and outward through 55 the opening 7 and the air to support combustion has

free passage upward between the bars and thus mingle and mixes with the gas which is burned as it reaches the ring 6. By the construction of burner herein described, I have attained a maximum simplicity, durability, and efficiency. It is apparent that the burner may be readily detached when required for cleaning or other purposes. The coil B is quickly heated by the burner and the water entering the same through the pipe 8^a, that connects with the regulator casing D, is drawn off from the pendent pipe 9 on the opposite side of the heater A.

The details of construction of the gas and water regulator will be understood from the following description, having reference to Figs. 5 to 8, inclusive (Sheet 70 2). As indicated in Figs. 5 and 7, the casing D is divided vertically by a partition 10 thus forming a water compartment 11, and a gas compartment 12, the latter being the smaller. The water compartment is again practically divided by a piston valve 13 into 75 two chambers, the water being received through pipe 8 into the lower chamber and discharged by pipe 8^a from the upper chamber. These two chambers are connected by means of a by-pass 10^a which is a passage formed in the partition 10. The passage of water 80 from the lower chamber into the upper one, and thus from pipe 8 to pipe 8^a is obviously controlled by the valve 13, which is shown in Fig. 5 in position to close the lower end of the by-pass, or, in other words, cut off for a time the passage of the water. When raised 85 sufficiently to uncover more or less of the mouth or lower end of the by-pass 10^a, it is obvious that water will pass from the lower chamber to the upper, or from pipe 8 to pipe 8^a and thus into the coil B.

The gas compartment 12 is subdivided by a cross-partition 14 having an opening to receive the guide or wing portion 15^a of the bevel valve 15. The valve seats upward and its stem 16 is connected by an eye with the elongated arm of the lever 17, while the stem 18 of the water valve 12 is similarly connected with the 90 shorter arm of said lever. The latter is arranged horizontally and provided with a spherical bearing 17^a, see Fig. 9—which is seated in a corresponding cavity or groove in a tapered bearing 19, the same being arranged horizontally in an opening in the main partition 10. As shown in Fig. 10, the bearing comprises a tube having at its larger flared end a radial flange 19^a through which pass screws that secure it to the partition 10. The lever 17 is provided with a cylindrical boss, or enlargement, 17^b, at a point adjacent to the 95 spherical bearing 17^a, and the inner side of the same is undercut, or formed on the arc of a circle described from the center of the spherical part 17^a. A soft rubber tube 20 is applied to the tapered bearing 19 and extends over the joint between its cylindrical or smaller 100 end and the adjacent boss or enlargement 17^b of the lever 17. The boss is grooved or otherwise roughened,

and a metal ring 21 is applied to hold the rubber tube tightly engaged therewith. The said tube is also clamped in the opening provided in the partition 10, so that a gas- and water-tight joint is formed between 5 the two adjacent gas and water chambers, and at the same time provision is made for the easy oscillation of the lever 17 corresponding to the change in the pressure of the water and gas, as will now be described. The lower end of the water compartment is closed by 10 a screw plug 22, and the corresponding end of the gas compartment by a screw plug 23. These plugs may be easily removed for cleaning the respective compartments.

When the hot water bib attached to the extension 15 of the coil pipe 9 is closed, the water pressure is the same on both sides of the piston valve 13, and the latter being practically weighted, that is to say, heavier than the gas valve 15, it maintains the position indicated in Fig. 5 so long as the water pressure is thus 20 equalized, and thus closes the by-pass 10^a. In this position the gas valve 15 is held to its seat so that no gas passes from the lower to the upper chamber. When, however, the hot water bib is opened, the pressure of 25 the water is necessarily decreased in the upper chamber, that is to say, the portion of compartment 11 above the piston valve 13, and hence the greater pressure existing in the lower chamber or portion of the compartment raises the piston valve 13, thus opening the port or by-pass 10^a. The distance to which the 30 valve 13 will be raised will correspond of course to the quantity of water drawn off. Such movement of the valve 13 tilts the lever 17 so that the gas valve 15 is lowered or moved off its seat, the movement corresponding exactly to the movement of the water valve 13, 35 whereby an amount of gas is allowed to pass from the lower chamber of the compartment 12 into the upper one. By these means the amount of gas allowed to pass to the burner is always exactly and properly proportionate to the quantity of water drawn off, so that 40 combustion and heat are always maintained in the required degree. The passage of water and gas will be further understood by reference to Figs. 1 and 2, where the water-inlet pipe is indicated by 8, the water-exit pipe by 8^a, the gas inlet pipe by 8^b, and the gas 45 exit pipe by 8^c—see Fig. 1. When no more hot water is drawn off, the balance of pressure in the compartment 10 is restored and the water valve 13 resumes the position indicated in Fig. 5 and consequently draws the gas valve 15 to its seat, thus cutting off further 50 flow of gas. It is obvious that the gas must be supplied to a pilot tip or burner for maintaining the igniting flame at the burner proper.

As shown in Fig. 5, the top corner of the casing D is made detachable from the main portion or body, it being secured by screws passing through valves resting upon a gasket. By removing this portion of the casing, the entire operative parts may be removed and replaced in a very short time and at small expense, without the aid of an expert mechanic for the purpose.

It will be understood that the pipe 9 may be extended to all parts of the house or building in which the heater is placed, and that it will be provided with as many bibs as necessary for drawing off hot water at any desired points. It will be further seen that the upper and lower ends of the water piston or valve 13 65 are beveled, thus forming practically knife edges, which when the piston moves up or down, serve to cut away deposits on the side of the cylinder, due to corrosion or impurities, thus insuring free action of the valve so that it is practically impossible that it should 70 stick. This feature is of practical importance, since accidents have occurred in this class of automatic water heaters, by reason of the valve sticking, so that gas would continue to flow after the water had been 75 cut off.

I claim—

1. In a water-heater, the combination with a heating coil, a burner, and gas and water pipes, of regulating mechanism comprising a casing having a main vertical partition provided with an opening in its upper portion, 80 gas and water compartments located on opposite sides of the said partition and each provided with gas and water inlets and outlets, the gas compartment having a transverse partition with an opening and valve seat, differential gas and water valves arranged between the respective 85 inlets and outlets, a pivoted oscillating lever extending through the opening in the vertical partition and connected with said valves, the lever having a spherical enlargement constituting its bearing point, a rigid tube secured in such opening and having a spherical seat for 90 the lever, the lever having also a circular boss adjacent to the spherical seat, and a soft rubber tube inclosing the rigid tube and secured to the boss, as and for the purpose specified.

2. In a water and gas regulating mechanism for water 95 heaters, the combination with the casing having a main vertical partition provided with an opening, adjacent gas and water chambers located on opposite sides of the said partition, and the latter being provided with a water by-pass, of differential water and gas valves, and means for 100 operatively connecting the same, consisting of a transverse lever loosely connected with the stems of the respective valves, a tube secured in the said opening in the main partition and provided with a seat for the pivot of the lever, and a soft rubber tube inclosing the joint of the 105 lever with the tube and thus serving to form a water- and gas-tight joint, as described.
